ADJUSTABLE SIGHT MOUNT FOR FIREARMS

Frank F. Burton, Mount Carmel, Conn., assignor, by mesne assignments, to Western Cartridge Company, a corporation of Delaware

Application April 9, 1937, Serial No. 135,969

7 Claims. (Cl. 33—56)

This invention relates to an improvement in mounts for the sights of firearms, and more particularly to mounts which provide for either or both vertical adjustment to compensate for changes in range, etc., and lateral adjustment to compensate for various wind velocities.

One of the objects of the present invention is to provide a superior adjustable sight-mount of the type described, and characterized by simplicity, reliability and effectiveness.

A further object is to provide a superior adjustable sight-mount of the character referred to, in which lost motion is eliminated or so minimized as to be negligible.

Another object is to provide a superior sight-mount of the character referred to, which may be readily and conveniently adjusted in either direction to definite settings.

With the above and other objects in view, as will appear to those skilled in the art from the following disclosure, this invention includes all features in the said disclosure which are novel over the prior art and which are not claimed by me in a separate application.

In the accompanying drawings, in which certain modes of carrying out the present invention are shown for illustrative purposes:

Fig. 1 is a view in left-side elevation of an adjustable sight-mount embodying the present invention, with the intermediate portion of the body-member broken away;

Fig. 2 is a broken view thereof in right-side elevation, with the forward portion of the body-member broken away;

Fig. 3 is a top or plan view of the rear portion of the sight-mount;

Fig. 4 is a view thereof in front-end elevation;

Fig. 5 is a vertical sectional view taken on the line 5—5 of Fig. 1;

Fig. 6 is a similar view taken on the line 6—6 of Fig. 1;

Fig. 7 is a vertical sectional view taken on the line 7—7 of Fig. 5;

Fig. 8 is a horizontal view taken on the line 8—8 of Fig. 5;

Fig. 9 is a horizontal sectional view taken on the line 9—9 of Fig. 6;

Fig. 10 is a perspective view of the windage-slide;

Fig. 11 is a perspective view of the windage-slide take-up spring;

Fig. 12 is a similar view of one of the adjusting-screw heads;

Fig. 13 is a perspective view of the tension-

ing-nut of the adjusting-mechanism of the elevation-slide;

Fig. 14 is a similar view of the tensioning-spring of the adjusting-mechanism of the elevation-slide; and

Fig. 15 is a perspective view of the end- or take-up plate of the body-member.

The particular adjustable sight-mount herein chosen for illustration includes a body-member, generally designated by the numeral 20, and comprising a body-head 21 and a forwardly-extending body-tang 22, which latter is provided in its inner or right face with a horizontal dovetail groove 23 adapted to receive and be longitudinally adjustable with respect to a suitable dovetail lug or rib (not shown) upon the receiver or other suitable part of a firearm structure. For the purpose of adjustably locking the body-member in place upon such a dovetail rib, the body-tang 22 is provided with two thumb-screws 24—24 and a kerfed plug-screw 25.

Applied to the rear end of the body-head 21 is an end- or take-up plate 26 which provides an adjustable rear wall for a dovetail groove 27 extending vertically through the right or inner face 25 of the said body-head. The said dovetail groove 27 receives, with capacity for vertical sliding movement, the vertical arm 28 of an elevation-slide, designated as a whole by the numeral 29, and of substantially L-shaped form. The said elevation-slide also includes a horizontal arm 30 extending to the right from the upper end of the vertical arm 28.

The vertical arm 28 of the elevation-slide is of dovetail form in horizontal section, as particularly well shown in Figs. 8 and 9, to accurately fit the dovetail groove 27 in the body-head 21. As before noted, the end- or take-up plate 26 provides the rear wall of the groove 27, just referred to, and for the purpose of insuring against looseness, the inner edge of the said plate 26 may be adjusted toward the adjacent edge of the arm 28 by means of two (more or less) take-up screws 31—31 (Fig. 1). As shown particularly well in Figs. 8, 9 and 15, the outer edge of the end- or take-up plate 26 is provided with a vertical fulcrum-rib 32 bearing against the rear edge of the body-head 21 and providing a fulcrum upon which the plate 26 may be rocked by the take-up screws 31—31.

The elevation-slide 29 is formed with a finger 33 offsetting to the left from the upper end of the arm 28 and in effect forming a continuation of the oppositely-extending horizontal arm 30 of the said slide. The finger 33, when the eleva-

25

35

40

50

55

tion-slide is in its depressed position, lies within an upwardly-opening transverse notch 34 formed in the adjacent upper edge of the body-head 21. At its lower end, the arm 28 is formed with a finger 35 offsetting in the same direction as the finger 33, before referred to, and accommodated within a vertically-extending groove 36 formed in the inner or right face of the body-head 21 and intersecting the lower end thereof.

10 The upper wall of the groove 36, above referred to, constitutes in effect a threaded nut 37 into which is threaded the shank of a vertically-extending elevation-adjusting screw 38. The said screw 38 extends at its lower end through an 15 unthreaded bearing-passage 39 in the finger 35 of the slide and has a kerfed head 40 bearing against the under-face of the said finger. The upper portion of the said elevation-adjusting screw passes through an unthreaded bearing-20 passage 41 formed in the finger 33 of the elevation-slide and into threaded engagement with the lower portion of a threaded bore 42 formed in a knurled adjusting-head 43. Threaded into the upper portion of the bore 42 in the said adjusting-head 43 is a headless kerfed binding-screw 44 which impinges against the upper end of the elevation-adjusting screw 38 and serves to firmly lock the latter to the said adjusting-head.

The under-face of the adjusting-head 43 is 30 formed with an annular series of downwardly-opening detent-recesses 45, each of which is adapted to be brought into registration with the rounded upper end of a detent-plunger 46 mounted for vertical reciprocation in an upwardly-opening cylindrical pocket 47 formed in the elevation-slide 29 adjacent the junction of its vertical and horizontal arms 28 and 30 respectively. The said detent-plunger is, as shown in Fig. 6, pressed upwardly by a helical spring 48 located 40 in the lower end of the pocket 47.

For the purpose of insuring the threaded connection of the elevation-adjusting screw 38 with the body-head 21, without axial backlash or play, there is mounted upon the said elevation-adjusting screw, immediately below the nut-like portion 37 of the body-head, a dished sheet-metal tensioning-spring 49 having a straight edge 50 which has sliding engagement with the adjacent face of the arm 28 of the adjusting-slide 29. Bearing against the under-face of the tensioning-spring 49 is a tensioning-nut 51 having a threaded bore 52 receiving the elevation-adjusting screw 38 and having opposite flat edges 53—53, either of which may be in sliding engagement with the 55 adjacent inner face of the vertical arm 28 of the elevation-slide 29, so as to restrain the said tensioning-nut against rotation. As will be noted by reference to Fig. 6 in particular, both the tensioning-spring 49 and the tensioning-nut 51 are 60 accommodated within the groove 36 in the body-head 21.

After the elevation-adjusting mechanism, just above described, has been assembled with the washer-like tensioning-spring 49 placed under 65 the desired degree of tension, the elevation-adjusting screw 38 and its adjusting-head 43 are threaded together until the upper face of the head 40 and the lower face of the adjusting-head 43 are firmly seated respectively against the under-face of the finger 35 and the upper face of the finger 33, whereupon the binding-screw 44 is screwed inwardly into firm engagement with the upper end of the shank of the elevation-adjusting screw 38, to thereby firmly lock the latter to the 70 adjusting-head 43.

For the purpose of conveniently gauging the vertical position of the elevation-slide 29, the left face of the body-head 21 is provided, as shown in Fig. 1, with a vertically-arranged series of indicia 54 providing an elevation scale which is 5 readable in conjunction with the pointed terminal of a forwardly-bent pointer-arm 55 of a sheet-metal elevation-indicator, generally designated by the numeral 56. The said elevation-indicator 56 extends to the right across the end-plate 26 10 and thence forwardly part way across the inner or right face of the vertical arm 28 of the elevation-slide 29 to which latter it is secured with capacity for slight vertical adjustment by a clamping-screw 57. To prevent the possible 15 canting of the elevation-indicator 56, the end thereof opposite its pointer 55 is turned inwardly to form a guide-flange 58 snugly fitting a guide-groove 59 formed in the inner or right face of the arm 28 of the slide. 20

For the purpose of further assisting the marksman in adjusting the elevation-slide 29, the periphery of the hub-portion 60 of the adjusting-head 43 of the elevation-adjusting screw 38 is provided with an annular series of indicia corresponding in number to the number of detent-recesses 45. 25

The horizontal arm 30 of the elevation-slide 29 provides mounting-means for a windage-slide. The said horizontal arm or mounting-member 30 for the windage-slide is bifurcated, as shown particularly well in Figs. 3, 8 and 9, by a notch-like guide-way 61 which is cylindrically contoured in cross-section and may be conveniently produced by a drilling or milling operation. Extending 35 into the notch-like guide-way 61, just referred to, with capacity for reciprocating movement free of the side walls thereof, are the cylindrically-contoured central portions of two spaced-apart resilient arms 62 and 63 offsetting from a 40 horizontally-adjustable windage-slide, generally designated by the numeral 64. The said windage-slide is provided with a threaded passage 65, which itself may be used as a peep-sight or, if desired and as shown, may receive the external- 45 ly-threaded tubular shank 66 of a peep-disk 67.

The windage-slide 64 is shaped to provide oppositely-extending horizontal bearing-shoulders 68—68 which are adapted to slide along the under-face of the horizontal arm 30 of the elevation-slide 29 and are held in snug engagement therewith by a sheet-metal tensioning-spring, generally designated by the numeral 69, and which is of substantially U-shaped form. Said tensioning-spring comprises two spaced-apart 55 arched arms 70—70 adapted to straddle the resilient arms 62, 63 of the windage-slide 64, and to bear both against the upper face of the arm 30 of the windage-slide 29 and the under-faces of the T-shaped terminals 71, 72 of the said resilient arms 62, 63. The arched arms 70—70 of the spring are integrally connected together by a side-bar 73 which is adapted to rest against the outer face of one of the arms 62 or 63, while the outer face of the other of such arms is engaged by the retaining-fingers 74—74, one of which latter is formed at the extremity of each of the said arms 70—70. 60

As thus constructed and arranged, the tensioning-spring 69 serves to prevent the canting of the 70 windage-slide 64 with respect to the elevation-slide, and assures that the windage-slide will accurately travel in a predetermined path. Each of the resilient spaced-apart arms 62, 63 of the windage-slide 64 is provided with a threaded bore 75

75, and in effect each of the said arms constitutes a nut-portion in threaded engagement with both of which is a windage-adjusting screw 76. The respective arms 62, 63 have their bores 75 threaded as described, and after such threading operation, the said arms are displaced with respect to each other in a direction substantially parallel with the axes of the said bores, so that all backlash between the windage-slide 64 and the said screw 76 is taken up. The displacement of the arms 62, 63, just referred to, may be either toward or away from each other and produces in effect the same result as that obtained by the tensioning-spring 49 in urging the tensioning-nut 51 away from the integral nut-like portion 37 of the body-head 21.

The windage-adjusting screw 76 is formed at one end with an integral kerfed head 77 which is formed in its inner face with a conical recess 78 (Fig. 8), which receives conically-contoured lips 79—79, one of which is formed upon the arm 30 on each of the respective opposite sides of the guide-way 61 therein. The head 77 is also recessed into the end of the said arm 30, as shown, 25 and by virtue of its conical recess 78 engaging with the lips 79—79, the material forming each of the opposite sides of the guide-way 61 is prevented from spreading or other displacement.

The windage-adjusting screw turns in an unthreaded bearing-passage 80 formed in the elevation-slide 29 and is threaded into the inner portion of a threaded bore 81 formed in a knurled adjusting-head 82 having a hub 83 provided upon its periphery with an annular series of indicia 35 for the purpose of aiding in the adjustment of the windage-slide 64. After the head 77 has been seated against the adjacent portion of the arm 30 of the slide 29 and the inner face of the adjusting-head 43 has been similarly seated against the 40 outer face of the finger 33 of the said slide, a headless kerfed plug-screw 84 is threaded into the outer end of the threaded bore 81 in the said adjusting-head and firmly seated against the adjacent end of the windage-adjusting screw 76.

45 The adjusting-head 82 corresponds in all essential respects to the adjusting-head 43, before described, and like the same is provided in its inner face with an annular series of conical detent-recesses 85 receiving the rounded outer end of a 50 detent-plunger 86 reciprocating in a pocket 87 formed in the slide 29 just to the rear of the screw 76. The said detent-plunger 86 is urged outwardly by a helical spring 88 located in the inner portion of the said pocket 87, as clearly shown in 55 Fig. 8.

As shown particularly well in Figs. 3 and 7, the horizontal arm 30 of the elevation-slide 29 has clipped over its forward edge a U-shaped sheet-metal windage-scale 89 secured in place by a 60 screw 90 and having a series of graduations thereon with which is adapted to register an index-mark 91 on the upper face of the adjacent arm 70 of the take-up spring 69.

In the structure above described, the elevation-slide 29 provides a mounting-member for the windage-slide 64 and in turn the body 20 provides a mounting-member for the said elevation-slide 29.

If desired and as indicated by broken lines in 70 Fig. 4, the windage-slide, instead of depending from the horizontal arm 30 of the elevation-slide, may be reversed to bring the threaded passage 65 therein in a plane above the part 30 just referred to.

75 By reference to the drawings and the foregoing

description, it will be seen that the present invention as illustrated herein provides an adjustable sight in which backlash or play has been practically eliminated, both as to the elevation-adjusting feature and the windage-adjusting feature, so that when either of the adjusting-screws 38 or 76 is turned in either direction, an instant and commensurate response is had from the part or parts being adjusted. Thus, for instance, if the user of the sight has turned the elevation-adjusting screw 38 to effect the upward movement of the elevation-slide 29, and should later decide that this elevation had been excessive, a slight reverse turning of the elevation-adjusting screw 38 will serve to effect the instant and proper degree of depression of the elevation-slide 29. In other words, the elevation-adjusting screw 38 does not require that it be turned in a reverse direction a considerable distance before it can effect the reverse movement of the slide 29. The same 20 elimination of lost motion is provided for the windage-slide 64 by the windage-adjusting screw 76 and associated parts.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. An adjustable sight-mount for firearms comprising: a mounting-member; a slide member; sight-means carried thereby; and adjusting-means constructed and arranged to shift the said slide-member and sight-means with respect to the said mounting-member and including an adjusting-screw and two complementary nut-like elements associated with the slide-member, one at least of which is in the form of a resilient arm, and both of the said nut-like portions being in threaded engagement with the said adjusting-screw under substantially constant axial tension and resiliently displaced with respect to each other along the axis of the said adjusting-screw, whereby the threads thereof are continuously forced into engaging relation to the threads of the adjusting-screw.

2. An adjustable sight-mount for firearms comprising: a mounting-member having two spaced-apart arms, each provided with a conically-contoured projection at a head-engaging end thereof; a sight-carrier adjustably carried by the said mounting-member; and adjusting-means constructed and arranged to shift the said carrier with respect to the said mounting-member and including an adjusting screw extending between the spaced-apart arms of the said mounting-member and having two opposed heads spaced from each other and respectively seated against oppositely-facing portions of the sight-structure, one of the said heads being threaded to the said adjusting-screw and helically adjustable with respect thereto, and locking-means constructed and arranged to lock the last mentioned head against rotation relative to the said adjusting-screw; one of the said heads being provided with a conically-contoured recess receiving the conically-contoured projections of the spaced-apart arms of the said mounting-member to restrain the said arms against separation.

3. An adjustable sight-mount for firearms 75

comprising: a mounting-member having a bifurcated portion providing a guide-way formed by and between two parallel fingers, each of the said fingers being provided with a retaining-lip at one terminal thereof; a sight-carrier mounted with capacity for reciprocation in the guide-way formed by the said fingers; and an adjusting-screw extending longitudinally of the guide-way in the said mounting-member and having a head provided with an annular recess in its inner face and fitting over the retaining-lips of the parallel fingers of the said mounting-member.

4. An adjustable sight-mount for firearms comprising: a mounting-member having a bifurcated portion providing a guide-way formed by and between two parallel fingers, each of the said fingers being provided with a conically-contoured retaining-lip at one terminal thereof; a sight-carrier mounted with capacity for reciprocation in the guide-way formed by the said fingers; and an adjusting-screw extending longitudinally of the guide-way in the said mounting-member and having a head provided with a conically-contoured annular recess in its inner face and fitting over the conically-contoured retaining-lips of the parallel fingers of the said mounting-member.

5. An adjustable sight-mount for firearms comprising: a body comprising a head-portion having a vertical guide-way therein and a relatively long and slender tang-portion extending horizontally forwardly from the said head-portion the said tang-portion depending vertically and being provided with a horizontal groove constructed and arranged to slidably receive a horizontal mounting-lug upon a firearm structure; locking-means for locking the said tang-portion to the firearm structure; an L-shaped elevation-slide having one arm vertically adjustable in the aforesaid guide-way in the head-portion of the body and its other arm projecting substantially horizontally across the firearm structure in a direction substantially perpendicular to the direction in which the tang-portion of the said head-portion extends; and a windage-slide carried by the substantially-horizontal arm of the said elevation-slide with capacity for horizontal adjustment with respect thereto.

6. An adjustable sight-mount for firearms comprising: a body-head; a slide-member shiftable with respect to the body-head; sight-means carried by the slide-member; and adjusting-

means operatively-connected with the slide-member and including an adjusting-screw and two complemental nut-like elements having threaded engagement with the adjusting-screw and being resiliently spaced apart along the said adjusting-screw, the said adjusting-screw and nut-like elements cooperating to cause sliding movement of the said slide-member, at least one of the said nut-like elements being associated with the said slide-member and being maintained thereby relatively-stationary with respect to the other nut-like element when the adjusting-screw is turned; at least the said one of the said resiliently-spaced-apart nut-like elements being under substantially constant axial tension urging it axially on the adjusting-screw with respect to the other nut-like element; whereby the threads of the said nut-like elements are maintained in closely-engaging relation to the threads of the adjusting-screw, and sensitive adjustment of the slide-member by the said adjusting-means operatively-connected therewith, is secured.

7. An adjustable sight-mount for firearms comprising: a body-head; a slide-member shiftable with respect to the said body-head; sight-means carried by the slide-member; and adjusting-means operatively-connected with the slide-member and including an adjusting-screw, two nut-like elements having threaded engagement with the adjusting-screw, and a laterally-distortable tension-spring mounted between and engaging adjacent faces of the nut-like elements to resiliently space the nut-like elements apart along the adjusting-screw, the said adjusting-screw and nut-like elements cooperating to cause sliding movement of the said slide-member, one of the said nut-like elements being engaged by the said slide-member and maintained thereby relatively-stationary with respect to the other nut-like element when the adjusting-screw is turned, and the said laterally-distortable spring acting on the said one of the nut-like elements to maintain it under constant axial tension and to urge it axially on the adjusting-screw with respect to the other nut-like element; whereby the threads of the said nut-like elements are maintained in closely-engaging relation to the threads of the said adjusting-screw, and sensitive adjustment of the said slide-member by the adjusting-means operatively-connected therewith, is secured.

FRANK F. BURTON.
